This is a continuation-in-part of my application for a patent filed on January 20, 1943, Serial No. 517,270, now abandoned, and relates to a cap retainer for tubes, bottles and other containers.

UNITED STATES PATENT OFFICE

2,376,786

CAP RETAINER FOR TUBES

Warren H. Lamm, Kildare, Okla.

Application August 19, 1943, Serial No. 499,270

8 Claims. (Cl. 220—30.6)

This invention relates to a cap retainer for tubes and has for an object to provide a simplified means for retaining the cap of collapsible tubes, bottles and other containers, in a closed position on the container or in a retracted position out of the way of the user, and which may be moved with minimum manual effort from one position to the other.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation of a cap retainer, constructed in accordance with the invention, applied to a collapsible tube.

Figure 2 is a view in elevation, taken at an angle of ninety degrees from that shown in Figure 1, and showing the cap retainer in dotted lines in retracted position.

Figure 3 is a cross sectional view taken on the line 3—3 of Figure 1.

Figure 4 is a side elevation, partly in section, showing a modified form of cap retainer.

Figure 5 is a cross sectional view taken on the line 5—5 of Figure 4.

Figure 6 is a side elevation of the cap retainer applied to a fabric or Cellophane tube.

Referring now to the drawing in which like characters of reference designate similar parts in the various views, 10 designates a tube of the dispensing type formed of soft metal and adapted to be collapsed for dispensing the contents. The tube is provided as is conventional with a threaded neck upon which the cap 11 is engaged to seal the contents air tight. For preventing the loss of the cap, the present invention provides the cap 11 with a stem 12 disposed centrally on, and extending upwardly from the cap, the stem being formed integral with a knurled disk 13 through the medium of which the cap may be screwed onto and off of the threaded neck of the tube and through the medium of which the cap may be retracted from the tube and disposed against the side of the tube in an out of the way position 55

as shown in Figure 2 when it is desired to dispense the contents of the tube. The cap, the stem and the knurled disk are formed integrally.

A disk 14 of any suitable material, such as fibre for example, is mounted on the stem between the cap 11 and the knurled disk 13. The disk 14 is substantially oval in contour and is provided on its transverse short diameter with a slot 15, see Figure 3, to rotatably receive the stem 12.

The tube 10 in the form of the invention shown in Figure 1 is provided on its conical shoulder with downwardly and outwardly extending lugs 16 which are disposed below notches 17 formed in the fibre disk 14 at the ends of the long diameter of the fibre disk.

An endless rubber band 18 is disposed astride of the stem 12, see Figure 3, and on opposite sides of the post the band is engaged through the notches 17 of the fibre disk 14 and then hooked over the lugs 16, to yieldably attach the cap to the tube and permit, after the cap is unscrewed by turning the knurled disk 13, the cap to be swung to the dotted line position shown in Figure 2 against the side of the tube, out of the way of the user when the contents are being dispensed, the elasticity of the rubber band holding the cap in the retracted position until it is desired to apply the cap again to the tube.

A modified form of the invention is shown in Figures 4 and 5 in which the cap 19, stem 20, disk 21, fibre disk 22, and tube 23 are the same as previously described but in this form of the invention the downwardly and outwardly extending lugs 24 are formed on the body of the tube instead of on the shoulder. Also in this form of the invention the endless rubber band 25 is not disposed astride of the stem 20 but one side of the band is engaged against the side of the stem and the same side of the band passes through the notches 26 in the disk 22, see Figure 5, and then is engaged underneath the lugs 24 while the other side of the band is directed around the curved wall of the tube 23 in alignment with the lugs 24. Thus the disk 22 is held assembled with the stem 20 and at the same time when the cap is unscrewed from the tube the cap may be retracted to released position against the tube and will be yieldably held in released position by the resiliency of the rubber band.

Another modified form of the invention is shown in Figure 6 in which the tube 27 is formed of fabric material or Cellophane material. In this form of the invention the cap 28, stem 29, knurled disk 30, and fibre disk 31 are the same as heretofore described. In this form of the in-

vention the rubber band 32 is engaged upon the top surface of the fibre disk 31 thence directed through the oppositely disposed notches in the fibre disk, and the ends of the band are secured to the tube 27 by strips of adhesive tape 33, adhesive Cellophane or similar material.

From the above description it is thought that the construction and operation of the invention will be fully understood without further explanation.

What is claimed is:

1. The combination with a collapsible tube of a cap forming a closure for the tube, a stem located centrally on and extending upwardly from the cap, means on the top of the stem for manipulating the stem to remove the cap from the tube, a slotted disk mounted on the stem between the tube and said means, the stem extending through the slot of the disk, lugs formed on the tube at the sides thereof, and a rubber band engaged across the top of the disk and contacting the stem, there being oppositely disposed notches in the disk, the band extending through said notches and being engaged with said lugs, said rubber band yieldably holding the cap applied to the tube and in retracted position against the side of the tube when removed from the tube.

2. The structure as of claim 1 and in which said means is a knurled disk.

3. The structure as of claim 1 and in which the rubber band is an endless loop disposed astride of the stem, directed through the notches in the disk, and looped around said lugs.

4. The structure as of claim 1 and in which the rubber band is an endless loop having one side engaged against the stem to hold the stem in the slot in the disk and having the other side directed underneath said lugs and extending along the side of the tube in alignment with the lugs.

5. The combination with a collapsible fabric or

Cellophane tube, of a cap forming a closure for the tube, a stem located centrally on and extending upwardly from the cap, means on top of the stem for manipulating the stem to remove the cap from the tube, a slotted disk mounted on the stem between the tube and said means, the stem extending through the slot of the disk, a rubber band engaged across the top of the disk and contacting the stem, the ends of the band extending downwardly to the tube, and adhesive means securing the ends of the band to the tube.

6. The structure as of claim 5 and in which said means comprises adhesive tape of fabric or Cellophane.

7. The combination with a collapsible tube, of a cap forming a closure therefor, a stem extending axially from the cap, means carried by the stem in spaced relation to the cap for manipulating the cap to remove it from the tube, a disk mounted on the stem between the tube and said means, the disk being provided with a slot open at one end through which the stem extends, the disk being provided at opposite sides of the stem with notches, and an elastic member connected to the tube and extending across the stem and through the notches, said elastic member contacting with that side of the stem facing the open end of the slot.

8. The combination with a collapsible tube, of a cap forming a closure therefor, a stem extending axially from the cap, means on the stem in spaced relation to the cap for manipulating the cap to remove it from the tube, a disk having a slot open at one end and mounted between the cap and said means with the stem extending through said slot, and an elastic member connected to the tube and disk and extending across the neck in contact with that side thereof facing the open end of the slot.

WARREN H. LAMM.
